UNITED STATES PATENT OFFICE.

JOHN HUTTON, OF NEW Utrecht, ASSIGNOR OF ONE-HALF TO JOHN W. FOWLER, OF BROOKLYN, NEW YORK.

CAR-VENTILATOR.

SPECIFICATION forming part of Letters Patent No. 380,440, dated April 3, 1888.

Application filed March 22, 1887. Serial No. 231,984. (No model.)

To all whom it may concern:

Be it known that I, JOHN HUTTON, a citizen of the United States, and a resident of New Utrecht, in the State of New York, have 5 invented a new and useful Improvement in Car-Ventilators, of which the following is a specification.

This invention relates to those car-ventilators which are designed to connect the interior of the car with the open air, so as to permit the escape of its vitiated atmosphere and the entrance of fresh air without exposing the passengers to drafts, and so that the ventilating-openings can be readily and quickly opened 15 and closed, or partly opened, at will. The present device is primarily designed for street-cars, but may be embodied in any car having a longitudinal "dome" in its roof.

This invention consists in certain novel combinations and arrangements of parts, herein-after claimed, whereby in the first place the ventilating-openings are located at the extreme top of the car, where the escape of air is most advantageous, and so as to be protected from 25 the weather by the eaves of the dome-roof, the requisite area of opening being obtained by multiplying small holes, so that when they admit air it is in numerous minute horizontal jets high above the passengers, while slides 30 for closing or partly closing said ventilating-holes are conveniently worked by levers, and at the same time slide rectilineally without either part being slotted, and, secondly, so that the customary side lights or ventilating-windows in the sides of the dome coat with said 35 ventilating-openings, and consequently may be and are constructed so as to open only to a very limited extent, being, as regards ventilation, mainly intended as outlets when the ventilating-openings do not suffice, while opening 40 them so as to admit downward blasts of wind or so as to admit rain or snow is prevented, as hereinafter set forth.

A sheet of drawings accompanies this specification as part thereof.

Figure 1 of the drawings represents a vertical longitudinal section in two parallel planes through a central portion of the top of a street-car illustrating this invention. Fig. 2 represents a horizontal section in the plane of the

ventilating-openings *v* seen at the top in Fig. 1, with a top view of the controlling-slides. Figs. 3 and 4 represent vertical sections on the lines 3 3 and 4 4, Fig. 1, respectively; and Fig. 5 is a perspective view of the actuating end 55 of one slide, with its lever and other appurtenances, on a scale of two to one as compared with the other figures.

Like letters of reference indicate corresponding parts in the several figures. 60

Immediately beneath the roofing-boards of the dome-roof *R*, I substitute for the customary solid upper stringer or top sill at each side a hollow sectional stringer, *A*, composed of perforated flat sides and a bottom strip. Within 65 this I place a pair of (or it may be one or more than two) sectional slides, *B*, having perforations which correspond with those in the sides of the stringer, so that in one position of the slide the perforations coincide and form the 70 ventilating-openings *v*, as represented at the left in Fig. 1 and more clearly in Fig. 3.

At mid-length of the car (or it may be at any convenient point) I provide each slide *B* with a thick terminal portion, *t*, correspondingly cutting away the front of the stringer *A* at this point to accommodate the same, and I mask this opening with a metallic cap-plate, *C*, attached at its ends to the stringer by screws and provided with a curved slot, *s*, Fig. 5, 80 through which a coupling-screw, *c*, is inserted into said terminal portion *t*, to couple to the slide a finger-lever, *D*, which is attached to said cap-plate by a fulcrum-screw, *f*, and provided near its free end with a locking-spring, 85 *l*. At this point the lever *D* is embraced by a keeper, *E*, attached to the inner edge of the bottom sill, *S*, of the dome side, as shown in Figs. 1 and 4, and having a pair of pockets, *m n*, Fig. 5, in either of which it is retained 90 by said spring *l* until sufficient force is applied to the lever by hand to overcome the spring. Each slide is thus held in one or the other of its positions (open or closed) represented, respectively, at the left and the right hand in 95 Figs. 1 and 2.

The several sections of which each slide *B* is composed work between the respective pairs of dome-roof ribs *R*, and are coupled together by their metallic "unions" *u*, flush with the 100

top of each section, and the thickness of which determines the depth of notch in each rib. The flexibility of said unions u permits the end section of the slide to accommodate itself 5 to operation by the lever D, as aforesaid. Outside of the stringer A said ribs R² extend the dome-roof to form the customary eaves, e, which are utilized to protect the ventilating- openings v and the slides B from the weather. 10 The dome-roof R and said stringers A are supported by short uprights or posts P, uniting said ribs R with said lower sills, S, and between these posts the customary ventilating- windows, W, are pivoted, but so as to limit their 15 opening movement to the small extent represented by dotted lines in Fig. 3. They thus form effective supplemental outlets in connection with said ventilating-openings v, as represented by arrows in Fig. 3, while opening 20 them to an objectionable extent is prevented. The main roof and its ribs R' are not affected by my present invention.

Having thus described my said improve-

ment in car-ventilators, I claim as my invention and desire to patent under this specification—

1. In a car-ventilator, the within-described perforated slides, each composed of several sections coupled together by flexible metallic unions, in combination with levers having fixed fulcrums and coupled directly to each slide at one end without slots in either part, substantially as herein specified.

2. The combination, in a car-dome, of stringers immediately below its roof, provided with lateral ventilating openings and means, substantially as described, for closing or partly closing the same at will, and side windows beneath said stringers, mounted on horizontal pivots and having a limited opening movement, substantially as herein specified, for the purpose set forth.

JOHN HUTTON.
